UNITED STATES PATENT OFFICE.

ROY ALEXANDER WEAGANT, OF NEW YORK, N. Y., ASSIGNOR, BY MESNE ASSIGNMENTS, TO RADIO CORPORATION OF AMERICA, A CORPORATION OF DELAWARE.

METHOD AND APPARATUS FOR RADIOSIGNALING.

Application filed February 7, 1919. Serial No. 275,557.

This invention relates to a method and apparatus for radio signaling and has for its object to prevent or reduce interference in radio reception, with particular reference to minimizing the effects of static disturbances.

In my co-pending application, Serial No. 181,458, I have disclosed my discoveries in regard to the nature of static disturbances, which appear to be propagated substantially vertically, and in another of my co-pending applications, Serial No. 275,555, I have described and claimed an antenna which becomes unresponsive to the desired signal waves to which it is tuned, when adjusted to a position normal to the advancing wave front. Such an antenna, although unresponsive to signals, continues to receive static impulses and this function or attribute may be utilized in various ways, as disclosed in that application referred to.

I have also demonstrated, as disclosed in my co-pending application Serial No. 275,554, that static impulses appear to be possessed of comparatively short wave length, although I am unable as yet to make more definite statements in regard to the actual or probable wave length of static waves.

If the wave fronts of vertically propagated static waves were strictly horizontal, then a strictly vertical antenna in the form of an ordinary open wire for instance, should not pick up static, because the longitudinal axis of the wire would be normal to the advancing wave fronts. That such an antenna is affected by static disturbances may be due to other causes, for instance the transmission of static waves may not always be strictly vertical although I have never found anything leading conclusively to the view that it is not strictly vertical. I know that static occasionally comes at considerable angles with the vertical but this is not the usual variety. There are cases comparatively rare in my experience for instance, in which the predominant static is that due to thunderstorms, and has a large horizontal component.

In view of these considerations, I have devised a new antenna and a method of operation by means of which static may be

excluded and only signals received. My new antenna, in the best form known to me at present, consists of a linear oscillator and differs from the ordinary antenna heretofore used, in that it is not grounded, its longitudinal axis is capable of adjustment in vertical and horizontal planes so that it is either strictly vertical or is in line with the static waves to be avoided, that is, normal to the wave fronts of such static waves, and my antenna preferably has no capacity area at top or bottom, although whether some form of such capacity areas may be used or not I do not at present know and cannot state.

Such a linear oscillator antenna may be pointed directly at the static and if the direction of travel of the static waves is not too nearly horizontal, the static will be eliminated and the signal received.

The receiving circuits including the detector circuit should preferably be interposed substantially at the middle of the length of the antenna for the best results, and directly in line with the antenna, or as nearly as possible in line therewith, instead of being located in a house off at one side as is customary, thereby avoiding as far as possible horizontally extending leads and connections.

The drawings illustrate a preferred form of apparatus for practising my new method of static elimination in which

Figure 1 is a diagrammatic side elevation of the apparatus, and

Figure 2 is a similar view at right angles to the other side or end of the apparatus.

Referring to the drawings, A represents a suitable frame or support adapted to be pivotally mounted for angular adjustment in vertical and horizontal planes. In this instance I have shown the frame A horizontally pivoted at B to a block C which is vertically pivoted at D on a post E of sufficient height to permit swinging the frame A about the pivot B. The block C extends outwardly beyond the post E so that the frame A has freedom of angular movement about the vertical pivot D.

The antenna, preferably in the form of a linear oscillator, comprises the wire F car-

ried by the frame A on suitable insulators G. Receiving circuits are interposed in the length of the antenna A substantially at the middle point and as far as possible directly in line with the antenna. As shown in this instance, variable coupling coils H are connected in the antenna and a variable tuning condenser J is interposed between the poles H. Variable tuning inductances 10 K are connected in the circuit of the antenna and any suitable form of detector circuit L is coupled to the coupling coils H by means of the variable coupling coil O. The detector circuit L is shown diagrammatically 15 for convenience of illustration and is assumed to be constructed with its circuits and connections extending as nearly in line as possible with the general direction of extent of the antenna F. The pivotally mounted 20 frame A and the antenna F carried thereby may be of any desired and convenient length suitable for receiving signals of the desired strength in the antenna. It may be found desirable for instance to mount a receiving 25 house for the receiving apparatus on an elevated platform P near the top of the pole E.

In the operation of the apparatus in radio 30 reception, the angular relation of the antenna F is adjusted relatively to the wave front of static impulses until said antenna becomes substantially unresponsive to said impulses but receives signals. This is equivalent to adjusting the angular position of 35 the antenna relatively to the directions of propagation of static impulses and signal waves until one effect goes out and the other remains. The antenna F may thus be positioned at an ineffective angle with respect to 40 the wave fronts of static impulses but at an effective angle with respect to the direction of propagation of desired signal waves, that is the antenna has no effective component with respect to the static waves to be avoided.

This arrangement is useful not alone for 45 avoiding static interference but also for avoiding interference from signals coming from a different direction. For example if 50 it is desired to receive from an aeroplane but to avoid the interference from another, as for example an enemy plane purposely interfering, it is only necessary to keep the antenna pointed at the interfering plane. 55 The signals from the other plane can then be received unless the two planes are too close together. With present day amplifying apparatus comparatively short and hence readily movable antennæ may be used.

60 I claim and desire to obtain by Letters Patent the following:

1. The method of minimizing static interference in radio reception with a directive antenna, such as a linear oscillator, an ungrounded antenna or an ungrounded linear

oscillator, which consists in adjusting the directivity of the antenna relatively to the horizontal plane until said antenna becomes substantially unresponsive to said impulses, and receiving signals in said antenna. 70

2. The method of minimizing static interference in radio reception, which consists in adjusting the angular relation of an antenna relatively to the horizontal plane until said antenna becomes substantially unresponsive 75 to said interference and receiving signals in said antenna.

3. The method of minimizing static interference in radio reception with an antenna in the form of a linear oscillator, which consists in adjusting the antenna into a position substantially at right angles to the wave front of static impulses, whereby it becomes unresponsive to said impulses, and receiving 80 signals in said antenna. 85

4. The method of minimizing static interference in radio reception, which consists in adjusting the angular relation of an antenna relatively to the horizontal plane until one effect goes out and the other remains. 90

5. The method of minimizing static interference in radio reception which consists in adjusting the angular direction of an antenna with respect to the horizontal plane and relatively to the directions of propagation of static impulses and signal waves to a position in which a desired ratio of signal to static is obtained. 95

6. The method of minimizing static interference in radio reception with a directional antenna, which consists in adjusting the directivity of the antenna with respect to the horizontal plane and relatively to the direction of propagation of static waves to a position in which the effect of static waves 100 is eliminated and receiving the desired signals with the antenna adjusted to this position. 105

7. In radio signaling, the method of preventing interference, which consists in adjusting the angular direction of an antenna with respect to the horizontal plane and relatively to the wave fronts and directions of propagation of electro-magnetic waves arriving from two different directions until 115 the effects due to waves from one direction are substantially eliminated and those from the other direction are retained.

8. The method of minimizing static interference in radio reception with an antenna in the form of a linear oscillator which consists in adjusting the angular direction of the oscillator with respect to the horizontal plane and horizontal direction to secure an ineffective angle with respect to the direction 120 of static impulses but effective with respect to the direction of propagation of desired signal waves and detecting said signal waves.

9. The method of minimizing static inter- 125

ference in radio reception which consists in adjusting the angular direction of an antenna with respect to the horizontal plane so as to have no effective components with respect to static waves.

10. In a radio signaling system, a directional receiving antenna responsive to high frequency electro-radiant waves, said antenna comprising means responsive to the electro-static component of said waves and having two axes about which it is rotatable whereby it may be rendered substantially unresponsive to waves from any given direction.

15. 11. In a radio signaling system, a directional receiving antenna responsive to high frequency electro-radiant waves, comprising oppositely extending capacitive elements and having vertical and horizontal axes about which it is rotatable whereby it may be rendered substantially unresponsive to waves from any given direction.

20. 12. In a radio receiving system, a directive antenna responsive to horizontally propagated high frequency electro-radiant waves and substantially unresponsive to waves from a certain direction relative thereto, said antenna comprising a linear oscillator and having two axes at right angles about which it is rotatable and whereby it may be positioned so that its unresponsive direction is inclined at an angle to the horizontal to eliminate waves from said direction, means for tuning said antenna to the horizontally propagated waves and receiving devices responsive thereto.

25. 13. In a radio signaling system, a directional antenna responsive to high frequency electro-radiant waves, said antenna comprising a linear oscillator having oppositely extending capacitive elements and an axis parallel to a line therebetween along which it is substantially unresponsive to waves, means for tuning the antenna to a desired wave, and a pair of axes about which the antenna is rotatable, whereby it may be adjusted to be unresponsive to waves from any given direction.

30. 14. In a radio signaling system a longitudinally extending directional antenna, said antenna being unresponsive along its longitudinal axis and tuned to a desired wave, and a pair of axes about which the antenna is adjustable for positioning the longitudinal axis to any desired angular relation with respect to the horizontal plane whereby interference from a certain direction may be eliminated.

35. 15. In a radio receiving system, a directive antenna substantially unresponsive to waves from a certain direction relative thereto, said antenna being positioned so as to be unresponsive to certain waves it is desired to eliminate and responsive to other waves of different azimuth, one of said waves being

horizontally propagated and the other propagated at an angle to the horizontal said antenna being adjustable with respect to the horizontal plane and relatively to the direction of propagation of static waves, means for tuning said antenna to the horizontally propagated waves and receiving devices associated with the antenna.

40. 16. In a radio signaling system, the combination of an antenna for receiving horizontally propagated waves in the form of a directional linear oscillator mounted for angular movement with respect to its angle with the horizontal plane, and receiving devices located substantially midway of the length of said antenna for receiving signals.

45. 17. In a radio signaling system, the combination of an antenna for receiving horizontally propagated waves in the form of a directional linear oscillator mounted for angular movement with respect to its angle with the horizontal plane, and receiving devices located substantially midway of the length of said antenna for receiving signals, said receiving devices being substantially in line with the direction of extent of said antenna.

50. 18. In a radio signaling system, the combination of an ungrounded directional antenna for receiving horizontally propagated waves in the form of a linear oscillator mounted for angular movement with respect to its angle with the horizontal plane, and receiving devices located substantially midway of the length of said antenna for receiving signals.

55. 19. In a radio signaling system, an antenna in the form of an ungrounded directional linear oscillator for receiving horizontally propagated waves mounted for angular movement in vertical and horizontal planes so that it may be pointed in the direction of propagation of static impulses and adjusted into a position normal to the wave front of said impulses, whereby the generation of currents in the antenna due to static impulses is avoided, and receiving devices located substantially midway of the length of said antenna for receiving signals from another direction.

60. 20. In a radio signaling system, an antenna in the form of a linear oscillator provided with a pair of axes about which it is rotatable affording provision for adjusting its azimuthal direction relatively to the wave fronts and directions of propagation of electro-magnetic waves arriving from two different directions until the effects due to waves from one direction are eliminated and those due to waves from the other direction are retained.

65. 21. In a radio signaling system, an antenna for receiving horizontally propagated signal waves in the form of a directional linear oscillator pointed in a direction at an

angle to the horizontal plane corresponding with the direction of travel of the static waves to be avoided, and having receiving circuits interposed in its length substantially in line therewith.

22. In a radio signaling system, an antenna for receiving horizontally propagated signal waves in the form of a directional linear oscillator pointed in a direction at an

angle to the horizontal plane corresponding to the direction of travel of the static waves to be avoided and having receiving circuits interposed substantially at the middle point in its length substantially in line therewith.

In testimony whereof I have signed this 15 specification.

ROY ALEXANDER WEAGANT.
